ATTORNEY

UNITED STATES PATENT OFFICE

WALTER C. ELZE, OF FOREST HILLS, NEW YORK, ASSIGNOR TO HAUCK MANUFACTURING COMPANY, OF BROOKLYN, NEW YORK, A CORPORATION OF NEW YORK

FORGE

Application filed April 7, 1931. Serial No. 528,295.

The invention relates to forges fired with gaseous fuels such as gas or atomized oil and preferably the latter. It relates more especially to a portable type of forge and is of the nature set forth in a prior U. S. Letters Patent No. 1,673,561. The furnace disclosed in said patent embodies a heating chamber with outlet opening or mouth conveniently located for the insertion and removal of the objects or material to be heated therein, for example, rivets; and provision is also made therein for causing the velocity of the products of combustion to be largely spent by the time they reach the space immediately above the mouth so that the working space in front of the forge will remain comparatively cool and accessible to an operator. The outgoing gases, furthermore, are more or less deflected away from the front of the forge.

The present invention has for its object to more effectively confine the gaseous products of combustion within the furnace space provided to enhance thereby the heating effect, as in the development within the said furnace space of a rotary motion of said gases rather than merely directing them through the furnace. Full advantage of the flame length may thus be had in causing it to travel over a maximum distance within a forge of predetermined size. The novel construction results, also, in the velocity of such gases being more completely spent before they reach the mouth of the forge.

A further object of the invention resides in the provision and arrangement of a furnace interior whereby the heated gaseous medium is directed substantially toward and over the articles retained on the hearth of the furnace and, also, in the provision and arrangement of a burner nozzle with respect to the said interior whereby a portion of the products of combustion are caused to recirculate within the interior of the furnace and the remainder travels forwardly in the direction of the outlet opening.

Another object of the invention resides in the arrangement of said outlet opening such that the outgoing gases are directed substantially vertically upward and without the provision of any further furnace elements,

special deflecting walls or baffles and the like being absent in the novel construction.

A still further object of the invention resides in the provision of a forge wherein the opening shall be solely at the top, there being no front or lateral exit portions associated therewith.

In carrying out the invention, a casing of refractory material is designed to afford a heating chamber into which a flame is arranged to be directed from a suitable burner suitably associated therewith. The said chamber in cross-section is substantially semi-circular over its upper half and is also substantially semi-circular over its lower half, the radius of curvature of the latter, however, being greater than that of the former and the rear walls merging. Thereby the lower half may be caused to project beyond the upper half to afford a mouth or opening at the top in accordance with the displacement.

An inlet duct to the furnace chamber is directed substantially tangentially to the upper half of the furnace space; and the wall providing the upper semi-circular portion of the furnace space is, preferably, continued slightly beyond into the lower semi-circular portion to check somewhat the outgoing products of combustion and assist in recirculating a portion of the incoming gaseous products, the remainder traveling forwardly in the direction of the opening and then vertically upwardly through the same.

The nature of the invention, however, will best be understood when described in connection with the accompanying drawing, in which:

Fig. 1 is a side elevation, partly in section, of the novel forge.

Fig. 2 is a front elevation of the said forge.

Referring to the drawing, 10 designates a suitable supporting frame upon which the heating chamber and various related apparatus of the forge is supported, including a fuel tank 11 which supplies liquid or gaseous fuel to a burner apparatus 12 attached to the back of the furnace portion proper. The burner 12 discharges into an inclined

duct or passageway 15 of the forge portion of the apparatus, which comprises a metal-bound casing 16 of refractory material. Said duct, in turn, delivers the burner flame 5 into a hollowed-out portion 17 of the casing 16, which in cross-section is substantially semi-circular. The hearth 18 of the forge is provided by a lower and also semi-circular hollowed-out portion 19 merging at the 10 back of the furnace space into the portion 17 but in cross-section is of a larger radius of curvature than that of portion 17. Portion 19 is displaced, therefore, forwardly with respect to the portion 17 and affords 15 thereby an outlet opening or mouth 20 through which the gaseous products of combustion may pass and through which articles to be heated, such as the rivets 21, may be inserted and removed. It is to be understood that while the lower portion 19 has been 20 shown as generally semi-circular in cross-section, the actual hearth portion thereof for receiving the articles need not be curved but may be constituted as a flat surface.

25 It is preferred, also, to continue the wall 22 bounding the hollowed-out portion 17 at its forward end slightly into the hollowed-out portion 19. This will tend to check outgoing gases and assist in returning a portion 30 of these gases, which have already acquired a circular motion, to the upper hollowed-out portion 17. The remainder of the gases continue forwardly about the lower end of wall 22 and are directed by the circular 35 lower portion substantially vertically upwardly and outwardly through the mouth 20.

This permits of an operator's approaching 40 closely the mouth of the furnace from the front of the forge as the same is relatively cool and accessible for manipulation of the articles to be heated and the handling of the same on the hearth.

45 Furthermore, by causing the gases to recirculate in part, a more elevated temperature is attainable in the forge and a greater radiant effect on the materials therein is had. Due to the semi-circular construction set forth, the products of combustion are caused, also, to more or less directly impinge 50 on and pass over the articles to be heated and thus a full benefit of the heating medium is attained.

I claim:

55 1. A forge comprising a casing of refractory material affording a heating chamber, said chamber in cross-section being substantially semi-circular over its upper half and substantially semi-circular over its lower half, the radius of curvature of the latter 60 half being greater than that of the former with the rear walls of the two halves merging, whereby the lower half is caused to project beyond the upper half to afford a mouth opening at the top, an inlet duct located at 65 the upper portion of the casing and directed

into the semi-circular upper half portion thereof and substantially tangentially thereto, and a burner discharging into said duct.

2. A forge comprising a casing of refractory material affording a heating chamber, 70 said chamber in cross-section being substantially semi-circular over its upper half and substantially semi-circular over its lower half with the forward wall of said upper half projecting slightly therein, the radius of curvature of the latter half being greater than that of the former with the rear walls of the two halves merging, whereby the lower half is caused to project beyond the upper half to afford a mouth opening at the top, 75 an inlet duct located at the upper portion of the casing and directed into the semi-circular upper half portion thereof and substantially tangentially thereto, and a burner discharging into said duct.

80 In testimony whereof I affix my signature.

WALTER C. ELZE.
